TIMING MECHANISM FOR WATCH AND
LIKE MOVEMENTS

Frank D. Urie, Elgin, Ill., assignor to Elgin National Watch Company, Chicago, Ill., a corporation of Illinois

Application June 16, 1932, Serial No. 617,640

1 Claim. (Cl. 73—51)

This invention relates to improvements in apparatus for timing watch and like movements to determine the error of such movements.

One of the features of the present invention is the provision of means responsive to the movement of the mechanism being timed, together with devices for counting the number of such movements, and means for energizing the counting devices for operation during a period of time determined by a standard timing device, so that the error of the particular movement being inspected produces an operation of the counting device which departs from the operation thereof which is produced by a mechanism operating in synchronism with the standard timing device.

Another feature of the present invention is the provision of a photo-electrical responsive device which operates according to the passage of light through the watch movement, this light being obstructed by a moving part of the watch mechanism being inspected, in conjunction with a timing device and a counter, whereby the number of impulses resulting from the operation of the photo-electrically responsive device is registered for a standard predetermined time whereby to indicate the error of the mechanism being inspected.

With these and other objects in view as will appear in the course of the following specification and claim, an illustrative form of practicing the invention is set forth on the accompanying drawings, in which:

Figure 1 is a diagrammatic view showing the connection of the several elements in this illustrative form of the invention.

Figure 2 is a side elevation of a mechanism for maintaining the timing circuit closed for a predetermined time interval.

Figure 3 is a plan view of the same.

Figure 4 is a vertical section through the illuminator and photo-sensitive element structures.

Figure 5 is a side elevation of the movement holder.

Figure 6 is a perspective view of the movement holder.

In these drawings, a source of light 10 and a condensing lens 11 project light upon a minute aperture 12 located, for example, in the pillar plate of a watch opposite the path of movement 50 of the teeth of the escape wheel W thereof: it is found in practice that a hole .012 inches in diameter is satisfactory. The other parts of the watch in alinement with the aperture are open to permit the passage of light through this aperture so that light is obstructed or permitted to

pass according to the prevailing position of the escape wheel teeth. The watch movement 13 is supported in a holder having an aperture 14 in its back in alinement with a corresponding hole in the shield 15 (Fig. 4) surrounding a photo-electrically responsive element P which is illustrated as being of the potassium type. A battery 16 is connected by conductor 17 with a solenoid 18 of a relay and thence by conductor 19 to one electrode of the photo-electric cell P. The other electrode of the cell P is connected by conductor 20 to the control electrode or grid 21 of an amplifier tube A. The cathode of the amplifier tube A is energized from a battery 22 through conductors 23, and a return conductor 24 is connected to the other terminal of battery 16. A branch conductor 25 connects the anode of the amplifier tube A to the conductor 19, so that the output current of the amplifier tube A will pass through the solenoid 18 of the relay. A biasing battery 26 is connected at its terminals to a potentiometer 27 which at one end is connected to the branch conductor 24, and has an intermediate tap connection to a conductor 28 having a control resistor 29 in series therein, and thus to the conductor 20.

Conductors 30 from a source of 110 volt alternating current, for example, are connected to an electrically operating counting device C, to contacts 31 closable upon energization of the relay solenoid 18, and by conductor 32 to an insulated contact 33 carried by a rocker arm 34 of a timing mechanism which will be described in detail hereinafter, and the current may thence pass to a fixed contact 35 and thus back to the mains. Conductors 40 are connected to a source of current impulses of standardized time interval, as for example, one impulse per second. These impulses energize the solenoid 41 and close contacts 42 of the time impulse relay 41, 42. When this relay is closed, current may flow from a part of battery 22 by conductor 43, over contacts 42, by conductor 44, to the fixed contact 45 and the open push-button 46 (being interrupted at these points), while a further tentative circuit exists from the movable contact 47 and the other contact of the push button 46, by conductor 48, the stepper solenoid 49, conductor 50, and one energizing battery conductor 23 back to the energizing battery 22.

In construction (Figs. 2 and 3), the stepper solenoid winding 49 causes reciprocation of the rocker bar 55 carrying a stepper pawl 56 on its end for engagement with the teeth of the ratchet wheel 57 which has oppositely directed cam pieces 58, 59 on its faces, for engagement with the con-

tact rocker bars 34, 34^a which carry at their opposite ends the insulated contacts 33, 47. The rocker arms 34, 34^a are pivotally mounted on a standard 60, and a similar standard 61 insulatedly supports the fixed contacts 35, 45. A spring 62 draws the rocker arms to produce a normal closure of the aforesaid contacts. A retaining pawl 63 prevents retrograde movement of the ratchet 57, while the pivotal mounting of the stepper pawl 56 on arm 55 and the spring 64 permit the upward return movement of the stepper arm 55 under the action of spring 65 when the solenoid winding 49 is deenergized. The threaded rod 66 passing through arm 55 has an adjustable nut 67 to limit the movement of the pawl 56.

The source of illumination 10 is preferably enclosed in a light-tight shield or housing 15^a which extends to support the condensing lens 11 (Fig. 4). The photo-electric element P has its base and the usual contacts mounted in a socket 71 (Fig. 4) and the housing 15 closes it against the penetration of light save through the watch movement 13. The movement holder (Figs. 4 and 5) has a back wall closed save for the opening 14, and has an open supporting frame 72, 73, 74 at the front into which the watch movement may be slid downwardly, the frame member 74 being slotted (Figs. 5 and 6) to receive the stem S of the watch movement and to reveal the opening 12 when the opening 12 is opposite the hole 14, in which position the watch movement is held by its engagement with the frame members 72, 73 and by the lateral pressure of a spring 75 located inside the frame piece 74.

In operation, with the counting device at a definite initial position, and with the source of light 10 energized, the cam pieces 58, 59 are located between the rocker arms 34, 34^a and hold the latter in such position that the contacts 33—35 and 47—45 are open. The regular time impulses coming by conductors 40 periodically close the relay contacts 42, but without any action upon the system. A watch movement is inserted into the holder frames 72, 73, 74, and the push-button 46 is depressed. The time impulses cause the closing of contacts 42 as before, and current now flows from battery 22 by conductor 43, contacts 42, conductor 44, push-button 46, conductor 48, solenoid winding 49, conductors 50 and 23, back to battery 22. Solenoid winding 49 causes the downward rocking of arm 55 and the stepper pawl 56 causes the ratchet wheel 57 to move a definite distance in a counter-clockwise direction (Fig. 2). This movement, if the time impulse conductors 40 are carrying impulses spaced at one second, is repeated every second. The cam pieces 58, 59 pass from between the rocker arms 34, 34^a so that the spring 62 causes closing of the contacts 33—35 and 47—45. Normally, this closure of the contacts occurs at the first impulse after the push-button 46 is depressed. The closure of contacts 47—45 short circuits the push button 46 so that it may be released without affecting the continued operation of the apparatus. The closure of contacts 33—35 tentatively establishes a circuit from one supply conductor 30 through contacts 33—35, conductor 32, relay contacts 31, and back through electrically operated counter C to the other conductor 30.

As the escape wheel, in this illustration of a watch movement, moves past the apertures 12, 14, each successive tooth momentarily shuts off the light. During each interval between the passage of such teeth, the illumination from source 10

passes to the photo-sensitive cell P and current flows from battery 16 by conductor 17, relay winding 18, conductor 19, through the cell P, to establish a charging potential upon the grid 21 of amplifier tube A with respect to its cathode. Current may now flow in the usual way through the amplifier tube A from battery 16 by conductors 24, 23 and passing to the anode of amplifier tube A and thence by conductors 25, 19, relay winding 18, and conductor 17 back to the battery 16. The energization of the relay winding 18 causes a closing of the contacts 31, so that a counting operation is performed in the counter C by current flowing from the main conductors 30. At the succeeding darkening of the cell P, the potential of the grid 21 in amplifier tube A changes and the flow of current is inhibited, so that the contacts 31 are opened again. This operation repeats itself for each succeeding tooth movement of the escape wheel past the apertures 12, 14.

Thus during the operation, the counter mechanism C is operating according to the number of passages of such teeth while the ratchet 57 is being stepped around synchronously with the standard time impulses arriving on conductors 40. The number of teeth on the ratchet wheel is proportioned according to the time interval during which it is desired to count the number of teeth passing the apertures 12, 12. At the end of a revolution of the ratchet wheel 57, the cams 58, 59 engage the rocker arms 34, 34^a and immediately break the contacts 33—35 and 47—45 whereby to interrupt the circuit through the counter C and also the circuit to the stepper solenoid winding 49. The ratchet wheel 57 thus remains at a standstill with the cams 58, 59 in the initial position, ready for a new operation when the push-button is depressed again.

The attendant now observes the reading of the counter C and determines therefrom the error of the particular watch movement. The movement is then adjusted by proper weighting of the balance wheel, for example, and a further test is made. In this way the errors are compensated until the watch registers standard time.

It will be noted that when the watch movement is removed from the holder, the device is ready for the insertion of a new watch movement, and hence little time is lost in the exchange and restarting of the apparatus.

It is obvious that the invention is not limited to the form of construction shown, but that many modifications may be made within the scope of the appended claim.

Having thus described the invention, what I claim as new and desire to secure by Letters Patent, is:

An apparatus for counting the operations of a watch and like movement having an escape wheel with a periodically moving part and which is open opposite the escape wheel, including a photo-sensitive cell, a light-tight housing surrounding said cell and having an aperture therein, a holder carried by the housing for supporting a watch movement in predetermined position with the path of the moving part of the escape wheel opposite said aperture, means for directing a ray of light through said movement and aperture and through the path of said moving part onto said cell, an electromagnetically operable counting mechanism, a ratchet wheel having cam means thereon, a solenoid and means moved thereby for advancing the ratchet wheel step by step, a source of standard time impulses, switch means positive-

ly moved to open position by said cam means at a predetermined position of said ratchet wheel, and circuit means extending through said switch means connecting said cell to said counting mechanism and said source to said solenoid so that the circuits delivering energizing current to said

solenoid and mechanism are opened at said switch means to terminate a counting operation, and means for connecting said source to said solenoid separately from said switch means for initiating a counting operation.
